BOW HOLDER

Stephen F. Kayn, New York, N. Y., assignor to
 Delamere Company, Inc., a corporation of
 Delaware

Application July 1, 1935, Serial No. 29,251

1 Claim. (Cl. 132—47)

This invention relates to a bow holder, and more particularly to a device for holding a bow or ribbon in the hair.

Among the objects of the invention are to provide a device of pleasing appearance which will securely hold a bow or ribbon; which can be easily opened and closed to insert or remove the bow; which affords a firm frictional grip on the hair so that the device will not slip or move out of place; and which is simple and inexpensive to manufacture.

With the foregoing and other objects in view, the invention comprises the novel arrangement, combination and construction of parts hereinafter described and illustrated in the accompanying drawing, in which:

Figure 1 is a front view showing the device with a bow retained in the holder;

Fig. 2 is a front view of the device showing the holder open;

Fig. 3 is a side view thereof showing the holder closed;

Fig. 4 is an enlarged top plan view;

Fig. 5 is a vertical cross-section of a modification; and,

Fig. 6 is a front view of the same.

The device comprises a spring clasp, in the nature of a hairpin, comprising two legs 10, 11, and a connecting spring loop 12 which latter urges the legs into contact with each other so as to effect a firm frictional grip on the hair in use.

A plate 13 is affixed to the front face of the upper end portion of leg 10 by solder or other suitable means. This plate supports the bow and preferably has a plurality of prongs 14 struck up from the material thereof, which prongs serve to hold the bow 15 from slipping sidewise when retained in the holder. The upper end of the plate 13 is bent up to form a transversely curved flange 16, which flange is formed with pintles at both sides thereof.

18 is a longitudinally curved bow holding member. A bracket or U-shaped member 19, best seen

in Fig. 4, is affixed to the upper end of, and extends downwardly from, the member 18. Eyes 20 are formed in the lower ends of the parallel side portions of member 19. The pintles 17 engage in these eyes to provide a hinge about which the bow holding member 18 may be swung into opened or closed position. 21 is a leaf spring having slots 22 at its ends which freely engage the sides of the U-member 19. In the next position of the bow holding member 18 this spring 10 presses against the upper edge of the flange 16 and provides the necessary pressure to hold said member closed against accidental opening.

A modification of the invention is shown in Figs. 5 and 6 of the drawing. In this form, the upper end of the supporting plate 13 is rolled into an eye 23 while the lower end is bent up to form a hook 24. The curved bow holding member 25, which in this instance is shown as made of resilient transparent material, such as celluloid, is hinged at its upper end 26 in the eye 23 and has an opening 27 at its opposite end for engagement with the hook 24 to hold it in closed position.

While I have shown and described certain specific embodiments of my invention, it is to be understood that the same may be modified in details of construction without departing from the scope of the invention as defined in the claim.

What I claim is:

A hair ribbon bow holder comprising a hair engaging member having a pair of vertically disposed spring legs formed to grip hair therebetween, a bow engaging plate secured to the outer face of the front leg at the upper end of the latter and extending longitudinally of said leg, a bow holding member pivoted to the top of said plate to cooperate therewith to hold the bow and having its lower end terminating adjacent the outer face of and between the ends of the said front leg, and means to hold the bow holding member in bow holding position.
